PRODUCTION OF DISTILLATE

Allen D. Garrison, Houston, Tex., assignor to
Texaco Development Corporation, New York,
N. Y., a corporation of Delaware

Application November 27, 1941, Serial No. 420,675

11 Claims. (Cl. 166—21)

This invention relates to a process for the production of liquefiable hydrocarbons from fluids flowed from distillate reservoirs, involving removing a distillate fluid from one or more producing wells, recovering liquefiable hydrocarbons from the fluid and returning residual gases to the same or a different producing formation.

The producing formations of distillate fields are characterized in that the hydrocarbons are considered to be present in the sand as a single homogeneous phase. The known distillate formations are usually at depths of 8,000 feet or more and the bottom hole pressures are normally from 3,000 to 5,000 pounds per square inch or above. As deep drilling continues it may be expected that distillate formations will be discovered at increasingly higher pressures.

Distillate fluids are distinguished from other fluids in producing formations in that they possess the property of undergoing condensation upon an isothermal reduction in pressure; i. e., they are subject to retrograde condensation. To avoid the operation of this phenomenon in the formation, and to comply with State laws in regard to conservation, it is necessary to maintain formation pressures by returning the residual gases to the formation. As a result of this requirement, the processes which have been proposed have embodied attempts in one way or another to recover the liquefiable hydrocarbons without reducing the pressure any more than necessary. However, because the maximum condensation of hydrocarbons has apparently taken place at pressures varying from about 1,000 to 2,000 pounds per square inch, depending upon the characteristics of the particular fluid, the processes in actual operation have involved reducing the pressure to some pressure below 2,000 pounds per square inch. Residual gases, therefore, have been obtained at a low pressure relative to the formation pressure and compression costs have been high.

Perhaps the simplest process that has been employed in the production of distillate has consisted in flowing the distillate fluid from the producing well through a choke to reduce the pressure to the desired point, cooling the fluid in one or more steps, separating liquefiable hydrocarbons which are condensed under these conditions, and compressing and returning the residual gases to the same or a different producing formation. It will be seen that where the formation pressures are in the neighborhood of 4,000 pounds per square inch and the condensation of hydrocarbons is accomplished at a pressure of the order of 1,200 to 1,500 pounds per square inch, the costs of compression

represent an important part of the costs of operating a process of this type.

It is an object of the present invention to provide a simple and efficient process for the production of a distillate field, which process is characterized in that compression costs are reduced, and the amount of processing of the fluid is lessened.

Other objects of the invention in part will be obvious and in part will appear hereinafter.

- 10 In accordance with the present invention the production of distillate is accomplished by a process in which a high density liquid is mixed with the distillate fluid in the producing well, preferably at about the depth of the producing formation, and the resulting mixed fluid is permitted to flow from the well due to the pressure of the formation. The mixed fluid is then passed from the well and is treated to separate three fractions: the high density liquid, the desired liquefiable hydrocarbons, which preferably consist of most of the butanes and substantially all of the pentanes and heavier, and the residual lighter gases. The separation step is preferably carried out at about the pressure at which the mixed fluid is removed
- 15 from the producing well, a pressure materially below the bottom hole pressure and of course below the pressure to which the residual gases would have to be raised to make possible their return to a high pressure formation.
- 20 In the case where the residual gases are to be returned to the same producing formation, after the separation of the mixed fluid, the pressure on the residual gases at the surface is raised a relatively small amount (e. g., 1,000 to 1,200 pounds per square inch) above well-head pressure. At the same time the high density liquid recovered in the separation is raised to the same pressure. The high density liquid and the residual gases are then mixed and passed into the injection well.
- 25 At the bottom of the well, preferably opposite the formation, the residual gases and the high density liquid are permitted to separate, and the gases pass into the formation to maintain the pressure. The high density liquid is removed from the injection well and employed for admixture with distillate fluid in the production well in the manner described above.
- 30 While the mechanism and manner of operation of the process and the advantages obtained will be more or less obvious as the description proceeds, it may be of advantage to point out here the broad principle upon which the process operates. When flowing a distillate well in the normal way there is, of course, a reduction in the pressure of the fluid from the formation to the well head.
- 35
- 40
- 45
- 50

This reduction in pressure is due to two factors, the pressure of the column of fluid and friction of the tubing. By mixing the distillate fluid in the producing well with a high density liquid the difference in pressure between the formation and the well-head may be adjusted to any desired value. This is done by controlling the height and/or density of the mixed fluid and thereby the hydrostatic-head.

Another advantage which is obtained from this improved method of operation is an inherent cooling of the distillate fluid. When such a fluid is passed through a choke or pressure-reducing valve, some cooling is accomplished due to the Joule-Thompson effect. But such expansion is thermodynamically irreversible, and no available work is derived from such pressure reduction. The object of this invention is primarily the expansion of distillate fluids to recover liquefiable hydrocarbons by a method which stores the energy of expansion in recoverable form. The recoverable energy is used to repressurize the reservoir. There are also thermal advantages which result. The heavy liquid injected into the producing well and mixed with the well fluid serves also as a cooling agent. There is added to this the cooling effect of expansion of the gas while doing work in lifting the heavy liquid to the surface, and delivering it at a substantially increased pressure. With certain types of distillates, this cooling together with proper pressure reduction will provide satisfactory hydrocarbon recovery. With other cases where additional cooling or absorption become desirable, their incorporation in this improved method becomes more economical than would usually be the case since substantial cooling is already an inherent feature of the process.

In addition to saving in power, a major feature of this invention consists of the elimination of high pressure surface equipment. When using the residual gases for repressuring purposes the introduction of the high density liquid into the gases produces a relatively dense mixed fluid which at a relatively low surface pressure will produce a high bottom hole pressure in the injection well. As a result, the necessity for compressing the residual gases to a high pressure at the surface is eliminated.

It will be understood in view of the variable conditions encountered in distillate production that various types of high density liquids may be used in the present process. In general it is preferred to employ a liquid in which hydrocarbons are substantially insoluble, although it is considered that in certain cases relatively heavy hydrocarbon oils may be found of advantage. It is also considered that in certain cases it may be found desirable to employ as the high density liquid water or oil weighted with heavy solids in finely divided form. However, I prefer to employ a water solution of a heavy material. As suitable heavy materials inorganic salts may be mentioned. In selecting a particular salt one factor which has not yet been referred to should be taken into account. As noted above, on flowing the mixed fluid from the formation to the head of the production well the temperature of the liquid is reduced. The final temperature employed at the well head may be reduced still further by cooling the high density liquid at the surface before introducing it into the production well. Accordingly, in selecting a salt solution, a solution should be selected which has a freezing point or point of separation of solute below the

temperature employed at the well head, which may be 32° F. or lower.

The salts which may be employed are any salts that produce a solution of the desired density, and the selection of a salt solution in a particular case may be made by reference to published information regarding the properties of the solutions. Salts which are of particular interest for use in making up the high density liquids are

10 halides, nitrates and sulfates of various metals which yield water-soluble salts with the acid radical. Specific examples of such salts are calcium chloride, zinc chloride, zinc bromide, zinc iodide, barium iodide, and cadmium chloride. Also of interest are potassium-chrom-alum, $K_2Cr_2(SO_4)_4$ and soda alum, $Na_2SO_4 \cdot Al_2(SO_4)_3 \cdot 24H_2O$. It will be understood that in order to achieve the desired density and freezing point a solution containing two or more salts may be used. For example, salts such as sodium bromide, sodium iodide, sodium nitrate or potassium carbonate may be used in conjunction with soda alum. Sodium silicate solutions are also of interest for use in the present process.

25 In general, it is preferred to employ a liquid having a density of above 1.2 grams per cc.; ordinarily the heaviest liquid that will operate being preferred. Because of ready availability, cheapness, and non-corrosiveness, solutions of calcium chloride are of particular interest. 30 Aqueous solutions of this salt can be prepared to have sufficient density and yet be stable at relatively low temperatures. To illustrate the properties of solutions of calcium chloride the following table is given. In this table the minimum temperature is the temperature at which separation of $CaCl_2$ from solution takes place.

Wt. percent $CaCl_2$	Specific gravity	Minimum temperature °F.
38.2	1.377	40
37.0	1.365	32
34.5	1.34	10
33.5	1.33	0
30.25	1.32	-10
30.17	1.315	-20

55 In order that the invention may be understood more fully the process will be described in connection with the accompanying drawing which represents in diagrammatic form a production well, an injection well, and above-ground apparatus elements employed in carrying out the present invention in accordance with one manner of proceeding.

The drawing illustrates a relatively simple application of the invention in which only a single producing well and only a single injection well will be described. Also, the operation will be described in connection with the return of residual gas to the same producing formation as that from which it is withdrawn. It will be understood that a number of producing and injection wells may be employed and in certain cases the gases may be returned to a different formation from the producing formation.

60 Referring to the drawing, A represents a producing well which taps a distillate formation. For the purposes of this description the well will be considered as being 8,000 feet in depth with a bottom hole pressure of about 4,200 pounds per square inch. The well A is provided with a casting 10 which contains perforations 12 opposite the producing sand 14. Disposed in the well is 65 a flow tubing 16 which is provided with an open

end 18. Disposed about the flow tubing 16 is a concentric tubing 22 of larger diameter. The tubing 22 is joined to the flow tubing with a fluid tight joinder at 24. Leading from the top of tubing 22 is a vent pipe 23 provided with a valve 25. Just above the joinder at 24 the flow tubing is provided with perforations 26. A valved line 28 leads from the top of flow tubing 16 to a separator 30.

The separator is of such volume and is so constructed as to permit the separation of three phases therein: residual gases, distillate, and the high density liquid. The residual gases may be passed from the separator through a valved line 32 directly to a compressor 34 and thence through line 36 into an injection well B. However, where the desired percentage of liquefiable hydrocarbons is not recovered in the separator, there may be placed between the separator and the compressor a recovery system, indicated generally at 31, which system may be an absorption or adsorption system or a system wherein the gases are subjected to additional cooling to remove additional distillate therefrom. The distillate may be removed from this system through valved line 33 leading to line 35 described below, and the residual gases are then passed to the compressor 34.

The high density liquid is removed from the bottom portion of the separator through a valved line 38 leading to a pump 40 and thence through line 42 and at point 43 into line 36 leading to the injection well. Distillate is removed from the separator through valved line 44, passes into line 35 and thence into distillate storage vessel 46. A line 48 provided with valve 49 leads from a pump 50 to the interior of tubing 22 in producing well A.

The injection well B is constructed so as to carry out the operation of the present process in the following manner. Similarly to well A, it is provided with a casing 52 which has perforations 54 opposite the producing formation. Within this casing there is an inner casing or tubing 56 having a diameter only slightly less than the diameter of the outer casing, and having a closed end 58. Disposed within this inner casing is an injection tubing 62 connected by means of valve 64 to line 36. A second tubing 66 is disposed within the tubing 62 and leads to valved line 68 connected with pump 50.

At some distance from the bottom of the well, the inner casing 56 is provided with perforations 72, by means of which gases may pass from the inner casing into the space between the two casings and into the formation. It will be noted that the outer and inner casings define an enclosed annular space which is open only at the perforations 72 and 54. As will appear from the following description, the perforations 72 may be located in some cases more than half way from the bottom of the well to the surface.

In carrying out the process in an apparatus of the type illustrated in the drawing, a high density liquid may be selected such that a column of the liquid equal in length to the depth of the well, or, where the liquid is not introduced into the bottom of the well, equal to the distance from the surface to the point of introduction, will exert a pressure only slightly above the pressure existing in the flow tubing at the point of introduction. Only a sufficient difference in pressure is required to cause the high density liquid to flow into the flow tubing.

The process may also be carried out using a liquid of higher density and regulating the height

5 of the column to yield the desired pressure at the point of introduction. By using a higher density liquid, the pressure of the column of liquid in the injection well may be several hundred pounds above the pressure existing in the bottom of the injection well. This latter manner of operating will be particularly described. In the present case the high density liquid used is a 34.5 per cent solution of calcium chloride 10 which has a density of about 1.34 grams per cc. A column of this liquid extending from the top to the bottom of well B will exert a pressure slightly less than 4700 pounds per square inch.

The process is begun with the tubing 22 filled 15 to a height of about 7200 feet with the calcium chloride solution which is fed in at a constant rate through line 48, trapped gas being released through line 23. The fluid flowing from formation 14 into the end 18 of flow tubing 16 passes the perforations 26 and there comes into intimate contact with the calcium chloride solution. The calcium chloride solution is fed in at a rate controlled by the size of the perforations 26 and the head of about 7200 feet in tubing 22 such that the solution is mixed with the distillate fluid 20 in the proportion of about equal parts liquid and fluid by volume. Since the fluid may have an average density of, for example, .20 gram per cc., and the liquid a density of 1.34 grams per cc. a mixed fluid may be produced having an average density of about .77 gram per cc. Due to the density of this mixed fluid and the frictional loss the well-head pressure may be of the order of 1200 pounds per square inch. Also, due to the 25 reduction in pressure of the fluid while doing work, and the cooling action of the liquid, which may be increased by cooling the liquid before introducing it into the well, the temperature is at a low point at which effective condensation of liquefiable hydrocarbons occurs; e. g., at a temperature of about 50° to 80° F.

In this operation, while the distillate fluid expands from about 4200 pounds per square inch gage to about 1200 pounds per square inch, the 30 high density liquid is compressed from 0 pounds per square inch to 1200 pounds per square inch. Under these conditions the mixed fluid is flowed through line 28 to separator 30. The residual gases are removed from the upper portion of the separator through line 32, and, if no further treatment is necessary, are passed directly to compressor 34 where they are compressed to a 35 pressure of, for example, 2400 pounds per square inch. The desired liquefiable hydrocarbons or distillate are removed through line 44 and are collected in distillate storage vessel 46. The high density liquid is removed from the bottom of the separator through line 38 to pump 40, wherein the pressure on the liquid is raised to about 2400 40 pounds per square inch, and passed through line 42, and, at point 43, into admixture with the residual gases flowing in line 36. The resulting mixed fluid is then passed through tubing 62 into the enclosed bottom portion of inner casing 56 which forms a zone 59. Since this mixed fluid 45 may have an average density of the order of .76 gram per cc., the pressure in the inner casing 56 in the neighborhood of the formation may be, for example, 4700 pounds per square inch. Under the quiescent conditions existing in zone 59, the gas will separate from the high density liquid and will pass up and through the perforations in inner casing 56 and into the formation for maintaining formation pressures. The high density liquid settles and is removed from the injection well

through flow tubing 66 and into line 68 leading to pump 50. This pump is operated merely so as to regulate flow from injection well B to producing well A. Therefore, the high density liquid under substantially atmospheric pressure will flow through line 48, valve 49 and back into tubing 22.

In certain cases it may be found desirable to subject the mixed fluid flowing in line 28 to a limited amount of cooling. This may be done so as to replace the recovery system 31 or in addition to this system. Although the temperature of the mixed fluid at the well head will be below the temperature of ordinary hydrate formation, because of the presence of the calcium chloride or other salt solution no difficulties due to the formation of hydrates will be experienced.

As previously indicated, in some cases it may be necessary to employ a recovery system in addition to the separator. The general operation of the process in such case will not differ materially from that described.

It will be noticed that it is necessary to compress the residual gases to only a few hundred pounds above the pressure at the well-head, thus simplifying compressor equipment and reducing power costs for this operation. With regard to the extent of this rise in pressure, this will be dependent upon the density and amount of high density liquid used, the depth of the well, and the formation pressure. In any case, the pressure of the residual gases after compression will be far below the normal well-head pressure of the production well, and of course even farther below the pressure normally required to return residual gases through an injection well to the formation.

In selecting the high density liquid it is generally preferred to select a liquid such that the hydrostatic head of the liquid in the injection well is about equal to the repressuring pressure i. e., the repressuring pressure less the pressure lost by friction. Such a liquid will flow under easily controlled conditions to the producing well. Also, the flow of the liquid into the distillate fluid in the producing well may be controlled easily by regulation of the height of the column of liquid and the size of the perforations 26. In this connection, the size of these openings may be made adjustable; for example, by providing means for making tubing 22 rotatable relative to tubing 16 and means operated by the relative rotation to reduce or enlarge the openings.

When using a relatively high density liquid, the amount of the liquid introduced into the distillate fluid is controlled so as to obtain the desired well-head pressure. For example, using a 50 per cent solution of zinc chloride, which has a density of about 1.57 grams per cc., in the above process, the height of the column of liquid in the producing well would be controlled to maintain it at about 6700 feet. When using this solution in an operation as described in the drawing, the solution would be mixed with the distillate fluid in the proportions of about 40 per cent of the solution and about 60 per cent of the distillate fluid by volume.

As indicated above, the drawing herein is merely diagrammatic in character to show the flow of fluids and no attempt has been made to show the elements in the relative sizes that would be used in practice.

From the foregoing it will be seen that the preferred operation of the process involves control-

ling the density or height or both of the high density liquid so as to obtain a pressure at the bottom of the column of liquid in the producing well about equal to the pressure of the distillate fluid. The rate of flow of the liquid is best adjusted by controlling the pump 50 to yield a mixed fluid of the desired density. The desired density of the mixed fluid is, of course, dependent upon the bottom hole pressure, the optimum pressure at the surface, and the depth of the well. In the normal case, conditions will be adjusted so that the pressure at the head of the producing well will be at about the bottom of the retrograde condensation range for the fluid in question. Thus, conditions may be adjusted so that the well-head pressure will be within the range of about 800 to 1600 pounds per square inch.

Obviously many modifications and variations of the invention, as hereinbefore set forth, may be made without departing from the spirit and scope thereof, and therefore only such limitations should be imposed as are indicated in the appended claims.

I claim:

25. 1. In the production of a distillate field wherein in a distillate fluid is flowed from a producing well tapping the producing formation, liquefiable hydrocarbons are recovered from the distillate fluid, and residual gases are returned through an injection well to a formation to maintain pressures, the process which comprises mixing the distillate fluid in the producing well with a high density liquid, permitting the resulting mixture to flow to the surface, whereby the temperature and pressure of the distillate fluid are reduced and liquefiable hydrocarbons are condensed, separating from said mixture liquefiable hydrocarbons, residual gases, and said high density liquid, passing a mixture of said residual gases and said high density liquid into the injection well at a pressure above the pressure at the head of the producing well, separating said last-mentioned mixture in the injection well into said residual gases and said high density liquid, passing said residual gases into the formation to maintain pressures, and returning the high density liquid to the producing well for admixture with the distillate fluid.
30. 2. A process in accordance with claim 1 in which the high density liquid is a liquid in which the hydrocarbons of the distillate fluid are substantially insoluble.
35. 3. A process in accordance with claim 1 in which the high density liquid has a density of at least 1.2 grams per cc. and comprises an aqueous solution of an inorganic salt.
40. 4. A process in accordance with claim 1 in which the high density liquid has a density of above 1.2 grams per cc. and comprises an aqueous solution of calcium chloride.
45. 5. In the production of a distillate field wherein in a distillate fluid is flowed from a producing well tapping the producing formation, liquefiable hydrocarbons are recovered from the distillate fluid, and residual gases are returned through an injection well to the formation to maintain pressures, the process which comprises flowing a high density liquid into the producing well out of contact with the distillate fluid so as to maintain a moving column of high density liquid therein, mixing the high density liquid with the distillate fluid at substantially the depth of the formation, controlling the pressure at which the high density liquid is introduced into the distillate fluid to a pressure adapted to cause the flow of the

high density liquid but being not substantially above the pressure of the formation, permitting the resulting mixture to flow to the surface, whereby the temperature and pressure of the distillate fluid are reduced and liquefiable hydrocarbons are condensed, separating from said mixture liquefiable hydrocarbons, residual gases and said high density liquid, raising the pressure on said residual gases and on said high density liquid, mixing said residual gases and said high density liquid at the raised pressure, passing the resulting mixture into the injection well, separating said last-mentioned mixture in the injection well into said residual gases and said high density liquid, passing said residual gases into the formation to maintain pressures, and returning the high density liquid to the producing well for admixture with the distillate fluid.

6. In the production of a distillate field wherein a distillate fluid is flowed from a producing well tapping the producing formation, liquefiable hydrocarbons are recovered from the distillate fluid, and residual gases are returned through an injection well to the formation to maintain pressures, the process which comprises flowing a high density liquid into the producing well out of contact with the distillate fluid so as to maintain a moving column of high density liquid therein, mixing the high density liquid with the distillate fluid in the producing well, the density of the high density liquid being such that the pressure of the column of liquid at the point of introduction into the distillate fluid is slightly greater than the pressure on the fluid, and the proportions in which the distillate fluid and the high density liquid are mixed being such that the resulting mixture will flow from the producing well at the surface at a selected reduced pressure within the retrograde condensation range of the distillate fluid, permitting the resulting mixture to flow to the surface, whereby the temperature and pressure of the distillate fluid are reduced and liquefiable hydrocarbons are condensed, separating from said mixture liquefiable hydrocarbons, residual gases and said high density liquid, raising the pressure on said residual gases and on said high density liquid, mixing said residual gases and said high density liquid at the raised pressure, passing the resulting mixture into the injection well, separating said last-mentioned mixture in the injection well into said residual gases and said high density liquid, passing said residual gases into the formation to maintain pressures, and returning the high density liquid to the producing well for admixture with the distillate fluid.

7. In the production of a distillate field wherein a distillate fluid is flowed from a producing well tapping the producing formation, liquefiable hydrocarbons are recovered from the distillate fluid, and residual gases are returned through an injection well to the formation to maintain pressures, the process which comprises flowing a high density liquid into the producing well out of contact with the distillate fluid so as to maintain a moving column of high density liquid therein, mixing the high density liquid with the distillate fluid at substantially the depth of the formation, controlling the height of the column of liquid to obtain a pressure of the column at the point of introduction into the distillate fluid slightly greater than the pressure on the fluid, permitting the resulting mixture to flow to the surface, whereby the temperature and pressure of the distillate fluid are reduced and liquefiable hydrocarbons are condensed, separating from said mixture liquefiable hydrocarbons, residual gases and said high density liquid, passing said residual gases into the formation to maintain pressures, and returning the high density liquid to the producing well for admixture with the distillate fluid.

5 hydrocarbons are condensed, separating from said mixture liquefiable hydrocarbons, residual gases and said high density liquid, raising the pressure on said residual gases and on said high density liquid, mixing said residual gases and said high density liquid at the raised pressure, passing the resulting mixture into the injection well, separating said last-mentioned mixture in the injection well into said residual gases and said high density liquid, passing said residual gases into the formation to maintain pressures, and returning the high density liquid to the producing well for admixture with the distillate fluid.

10 8. In the production of a distillate field wherein a distillate fluid is flowed from a producing well tapping the producing formation, liquefiable hydrocarbons are recovered from the distillate fluid, and residual gases are returned through an injection well to the formation to maintain pressures, the process which comprises flowing a high density liquid in which the hydrocarbons of the distillate fluid are substantially insoluble into the producing well out of contact with the distillate fluid so as to maintain a moving column of high density liquid therein, mixing the high density liquid with the distillate fluid at substantially the depth of the formation, controlling the height of the column of liquid to obtain a pressure of the column at the point of introduction into the distillate fluid slightly greater than the pressure on the fluid, permitting the resulting mixture to flow to the surface, whereby the temperature and pressure of the distillate fluid are reduced and liquefiable hydrocarbons are condensed, separating from said mixture liquefiable hydrocarbons, residual gases and said high density liquid, raising the pressure on said residual gases and on said high density liquid, mixing said residual gases and said high density liquid at the raised pressure, passing the resulting mixture into the injection well, separating said last-mentioned mixture in the injection well into said residual gases and said high density liquid, passing said residual gases into the formation to maintain pressures, and returning the high density liquid to the producing well for admixture with the distillate fluid, the density of the high density liquid being such that the pressure of a column of the liquid substantially equal in height to the depth of the injection well exerts a pressure substantially equal to the pressure required for passing said residual gases into the formation to maintain pressures, whereby the formation is repressured and the high density liquid flows from the head of the injection well.

15 9. In the production of a distillate field wherein a distillate fluid is flowed from a producing well tapping the producing formation, liquefiable hydrocarbons are recovered from the distillate fluid, and residual gases are returned through an injection well to the formation to maintain pressures, the process which comprises flowing a high density liquid in which the hydrocarbons of the distillate fluid are substantially insoluble into the producing well out of contact with the distillate fluid so as to maintain a moving column of high density liquid therein, mixing the high density liquid with the distillate fluid in the producing well, permitting the resulting mixture to flow to the surface, whereby the temperature and pressure of the distillate fluid are reduced and liquefiable hydrocarbons are condensed, separating from said mixture liquefiable hydrocarbons, residual gases and said high density liquid, passing a mixture of said residual gases and said high density liquid at a raised pressure into the injection

well, separating said last-mentioned mixture in the injection well at about the depth of but out of contact with the formation into said residual gases and said high density liquid, passing said residual gases to the formation to maintain pressures, and returning the high density liquid to the producing well for admixture with the distillate fluid.

10. In the production of a distillate field wherein a distillate fluid is flowed from a producing well tapping the producing formation, liquefiable hydrocarbons are recovered from the distillate fluid, and residual gases are returned through an injection well to the formation to maintain pressures, the process which comprises flowing a high density liquid in which the hydrocarbons of the distillate fluid are substantially insoluble into the producing well out of contact with the distillate fluid so as to maintain a moving column of high density liquid therein, mixing the high density liquid with the distillate fluid in the producing well, permitting the resulting mixture to flow to the surface, whereby the temperature and pressure of the distillate fluid are reduced and liquefiable hydrocarbons are condensed, separating from said mixture liquefiable hydrocarbons, residual gases and said high density liquid, passing a mixture of said residual gases and said high density liquid at a raised pressure into the injection well, separating said last-mentioned mixture in the injection well at about the depth of but out of contact with the formation into said residual gases and said high density liquid, passing said residual gases to the formation to maintain pressures, and returning the high density liquid to the producing well for admixture with the distillate fluid, the density of the high density liquid being such that the pressure of a column of the liquid substantially equal in height to the depth of the injection well exerts a pressure substantially equal to the pressure required for passing said residual

gases into the formation to maintain pressures, whereby the formation is repressured and the high density liquid flows from the head of the injection well.

11. In the production of a distillate field wherein a distillate fluid is flowed from a producing well tapping the producing formation, liquefiable hydrocarbons are recovered from the distillate fluid, and residual gases are returned through an injection well to a formation to maintain pressures, the process which comprises flowing a high density liquid into the producing well out of contact with the distillate fluid so as to maintain a moving column of high density liquid therein, mixing the high density liquid with the distillate fluid in the producing well, permitting the resulting mixture to flow to the surface, whereby the temperature and pressure of the distillate fluid are reduced and liquefiable hydrocarbons are condensed, separating from said mixture liquefiable hydrocarbons, residual gases and said high density liquid, passing a mixture of said residual gases and said high density liquid at a raised pressure into the injection well, separating said last-mentioned mixture in the injection well at about a depth of the formation into said residual gases and said high density liquid, passing said residual gases into the formation to maintain pressures, and returning the high density liquid to the producing well for admixture with the distillate fluid, the density of said high density liquid being such that the pressure of a column of the liquid substantially equal in height to the depth of the injection well exerts a pressure substantially equal to the pressure required for passing said residual gases into the formation to maintain pressures, whereby the formation is repressured and the high density liquid flows from the head of the injection well at substantially atmospheric pressure.

ALLEN D. GARRISON.
